US0D1097017S

(12) United States Design Patent (10) Patent No.: US D1,097,017 S
(45) Date of Patent: * Oct. 7, 2025

(54) PADDLE RACKET

(71) Applicant: AGUIRRE Y COMPAÑIA, S.A.,
Madrid (ES)

(72) Inventor: Leandro Arnanz Ramos, Madrid (ES)

(73) Assignee: AGUIRRE Y COMPAÑIA, S.A.,
Madrid (ES)

() Term: 15 Years

(21) Appl. No.: 29/923,250

(22) Filed: Dec. 28, 2023

Related U.S. Application Data

(63) Continuation-in-part of application No. 29/824,101,
filed on Jan. 21, 2022, now abandoned.

(57) CLAIM

The ornamental design for a paddle racket, as shown and described.

DESCRIPTION

FIG. 1 is a front view of a paddle racket showing my new design;

FIG. 2 is a back view thereof;

FIG. 3 is a left view thereof;

FIG. 4 is a right view thereof;

FIG. 5 is a bottom view thereof;

FIG. 6 is a top view thereof;

FIG. 7 is a perspective view of the front, left, and bottom sides thereof; and,

FIG. 8 is a perspective view of the back, left, and top sides thereof.

The broken lines are directed to the environment of the claimed design and form no part thereof.

1 Claim, 8 Drawing Sheets
